UNITED STATES PATENT OFFICE.

GEORGE ROUND, OF BROOKLYN, NEW YORK.

SASH LOCK.

Application filed October 1, 1921. Serial No. 504,715.

To all whom it may concern:

Be it known that I, GEORGE ROUND, a citizen of the United States, and a resident of the city of New York, borough of Brooklyn, 5 in the county of Kings and State of New York, have invented a new and Improved Sash Lock, of which the following is a full, clear, and exact description.

This invention relates to improvements 10 in sash locks, an object of the invention being to provide a sash lock which not only effectively locks the sashes against vertical movement, but also serves as an anti-rattler to prevent the annoying noises caused by 15 the movement of the sashes in the frame.

A further object is to provide a sash lock 20 which is burglar-proof, which can be manufactured and sold at a reasonably low price, and which will most efficiently per-

25 form the functions for which it is intended. With these and other objects in view the invention consists in certain novel features of construction, and combinations and arrangements of parts as will be more fully 25 hereinafter described and pointed out in the claims:

In the accompanying drawings—

Figure 1 is a broken view in vertical 30 transverse section illustrating my improved sash lock in its initial locking position.

Figure 2 is a similar view showing the sash lock in its full locking position to press the sashes against the beads and their frames and prevent rattling.

35 Figure 3 is a plan view showing the sash lock in its unlocked position.

Figure 4 is an end view of the sash lock.

Figure 5 is a view in side elevation of 40 my sash lock detached.

1 represents a window frame and 2, 3 and 4 are the ordinary beads of the window frame between which the upper and lower sashes 5 and 6 are mounted to slide.

45 My improved sash lock 7 is secured on the meeting rail 8 of the lower sash 6 and a keeper 9 is secured on the meeting rail 10 of the upper sash, which is the customary location for sash locks and keepers in general use.

50 My improved sash lock embodies a base 11, which is preferably secured by screws 12 to the meeting rail 8, and this base supports at an elevation therefrom a cylindrical casing or barrel 13. I preferably construct 55 the barrel and base of a single sheet of metal bent centrally forming the barrel 13, then

bent together forming a standard or upright web 14, then bent outwardly at right angles forming the base 11.

The keeper 9 is preferably made in similar fashion, having an upper cylindrical portion 15, a web 16 and a base 17, the latter secured to the meeting rail 10 of the upper sash 5 preferably by means of screws 18.

60 In the barrel 13 of the sash lock I provide a locking bolt 19, which is preferably of cylindrical form and fits the barrel or casing 13. This barrel or casing 13 has a cam slot 20 therein, through which an operating arm or finger 21 on the bolt 19 is projected, so that by moving the finger 21 in the cam slot 20, a longitudinal movement 70 is imparted to the bolt 19.

75 The bolt 19 at its inner or forward end is reduced in diameter as shown at 22, forming an annular shoulder 23 on the bolt. This smaller end 22 of the bolt fits within the cylindrical portion 15 of the keeper 9, it being understood that the cylindrical portion 15 of the keeper 9 is of appreciably less diameter than the bolt receiving cylindrical portion 13, so that when the bolt is projected forwardly, its smaller end 22 will project into the keeper and 80 form an effective lock holding the sashes against independent movement. A continued forward movement of the bolt 19 will cause the shoulder 23 of said bolt to engage the edge of the keeper 9 and exert a 85 pressure tending to force the sashes apart and jam or press the faces of said sashes against the beads 2 and 4 respectively to prevent rattling.

90 Applicant is aware that this extreme forward movement of the bolt in its function as an anti-rattler tends to force the meeting rails of the sashes apart, but this separation will be slight and in many cases will be 95 advantageous because of improved ventilation and at the same time securely locking the sashes and preventing rattling thereof. To prevent accidental longitudinal movement of the bolt 19, the extreme ends of the cam slots 20 are at right angles to the base 100 11, as shown at 24, so that when the finger 21 is forced into an extreme end of a slot, it will act as a positive lock against longitudinal movement of the bolt.

105 Various slight changes might be made in the general form and arrangement of the parts described without departing from the

invention, and hence I do not limit myself to the precise details set forth, but consider myself at liberty to make such changes and alterations as fairly fall within the spirit 5 and scope of the appended claims.

I claim:

1. A sash lock, comprising a casing, a keeper, a bolt slideable longitudinally of the casing and having a reduced end movable 10 into the keeper, said bolt having a shoulder at the base of said reduced end adapted to engage the keeper and tend to force the casing and the keeper apart when the bolt is moved in one direction, said casing having a 15 cam slot therein, and a finger on the bolt movable in the cam slot to impart longitudinal movement to the bolt.

2. A sash lock, comprising a bolt casing and a keeper, said casing and keeper each 20 composed of sheet metal bent forming aligned bolt receiving casings, upright webs and bases at the lower ends of the

webs, a bolt movable in the bolt casing and having a reduced end fitting within the keeper casing, a shoulder on the bolt adapted 25 to engage the end of the keeper casing, said bolt casing having a cam slot, and a finger on the bolt movable in the cam slot to impart longitudinal movement to the bolt.

3. The combination with a pair of vertically sliding sashes, of a bolt casing on the meeting rail of the lower sash, and a keeper on the meeting rail of the upper sash, a longitudinally movable bolt in the bolt casing, a reduced end on said bolt movable into 35 the keeper, a shoulder on the bolt adapted to engage the edge of the keeper, and means for imparting longitudinal movement to the bolt whereby the reduced end of the bolt locks in the keeper and the shoulder of the 40 bolt functions to force the sashes apart whereby rattling of the sashes is prevented.

GEORGE ROUND.
